BY

Lester V. Moulton,
ATTORNEY.

UNITED STATES PATENT OFFICE.

CHARLES O. ALLEN, OF GRAND RAPIDS, MICHIGAN.

CASTER.

SPECIFICATION forming part of Letters Patent No. 470,825, dated March 8, 1892.

Application filed May 8, 1891. Serial No. 392,075. (No model.)

To all whom it may concern:

Be it known that I, CHARLES O. ALLEN, a citizen of the United States, residing at Grand Rapids, in the county of Kent and State of Michigan, have invented certain new and useful Improvements in Casters; and I do hereby declare the following to be a full, clear, and exact description of the invention, such as will enable others skilled in the art to which it appertains to make and use the same.

My invention relates to improvements in casters for furniture and other articles; and its object is to provide spring-bearings for such casters that shall be cheap and durable, as hereinafter more fully described, and particularly pointed out in the claims, reference being had to the accompanying drawings, in which—

Figure 1 is a vertical section of a device embodying my invention; Fig. 2, a detail of the spring-socket, and Fig. 3 a vertical section of a modified form of my invention.

Like letters refer to like parts in all the figures.

25 A represents the lower end of the leg of a table or other article of furniture, having the usual cylindrical chamber A', within the axis of which is the pintle B of the caster, said pintle is reduced in diameter for a portion of 30 its length near the upper end, as shown at B', and is provided with a collar F where it joins the yoke D, between the arms of which is journaled the caster-wheel E. Said pintle is smaller in diameter than the chamber A' and 35 is surrounded with a spiral spring C, the outer diameter of which is slightly less than said chamber A' and the inner diameter slightly more than the pintle B, to permit free vertical movement of said spring and pintle within 40 the chamber A'. One turn of said spring C opposite the upper part of B' is made slightly smaller than the rest, so that when the upper end of the pintle B is crowded through and above the same the caster is retained thereby 45 and will not drop out. Said coil-spring rests at its upper end against the top of the chamber A' and extends a short distance below the end of the leg A, where it engages the collar F. The pintle being shorter than said 50 spring thus rests in a vertically-elastic socket. Said coiled spring may be supplemented by a conical spiral spring C'', made integral therewith, as shown in Figs. 1 and 2, which is lo-

cated beneath the leg and attached thereto by the upwardly-projecting outer end C'' of 55 said spiral spring. Said leg may also be made concave, as shown in Fig. 1, to permit of greater deflection of said spring. In Fig. 3 the supplementary helix is omitted, a shorter coil is used, and the pintle provided with an 60 enlarged cylindrical portion B'', upon which said spring rests, surrounding which is a thimble G, the internal diameter of which fits said enlarged portion B'' and is slightly smaller than the outer diameter of the spring 65 C'', thus being adapted to engage the said spring and hold it in place in the chamber A''.

I thus secure a cheap and durable spring-socket for the caster, which tends to relieve the jarring and noise when moving the furniture to which said caster is attached. It also tends to equalize the pressure when standing on an uneven floor and prevents the furniture from rocking upon two legs; also, when attached to any movable leg or 75 part of furniture it enables me to move the same with greater ease over any uneven surface, because of the yielding nature of the spring-socket, which permits the caster to rise without lifting so great a load. 80

What I claim is—

1. In a caster, a pintle having a reduced portion, as B', and a coiled spring surrounding said pintle, having a coil of reduced diameter opposite the reduced portion of the pintle, 85 substantially as described.

2. A caster-socket consisting of a vertically-elastic coil terminating at its lower end in a conical helix having an upwardly-projecting outer end, substantially as described. 90

3. The combination of a caster having a portion of reduced diameter, as B', and a collar, as F, and a coiled spring surrounding said pintle, having a turn of reduced diameter opposite the reduced portion of the pintle, said coil projecting above said pintle at its upper end, resting upon said collar at its lower end, and having an integral conical helix, substantially as described. 95

In testimony whereof I affix my signature in presence of two witnesses.

CHARLES O. ALLEN.
